UNITED STATES PATENT OFFICE.

HERMANN SCHULZE-BERGE, OF ROCHESTER, PENNSYLVANIA.

APPARATUS FOR GRINDING OR POLISHING GLASSWARE.

SPECIFICATION forming part of Letters Patent No. 447,700, dated March 3, 1891.

Application filed May 6, 1890. Serial No. 350,732. (No model.)

To all whom it may concern:

Be it known that I, HERMANN SCHULZE-BERGE, of Rochester, in the county of Beaver and State of Pennsylvania, have invented a new and useful Improvement in Apparatus for Grinding or Polishing Glassware, of which the following is a full, clear, and exact description.

The present invention refers to an improvement in apparatus for grinding or cutting flutes, lines, or geometrical figures upon glassware by means of revolving grinding wheels or disks.

The apparatus is illustrated on the accompanying two sheets of drawings, in which— Figure 1 is a front elevation thereof, partly in section. Fig. 2 is a vertical cross-section on the line II II of Fig. 1. Figs. 6 and 7 are an elevation and a cross-section of a modification of the apparatus. Figs. 3, 4, 5, 8, 9, 10, and 11 are detail views referred to hereinafter.

Like symbols of reference indicate like parts in each.

As shown in Figs. 1 and 2, the apparatus comprises a frame or bed-plate A, to which are secured several standards or brackets in which two spindles 4 and 5 are revoluble and are movable longitudinally in the same axial line. Between the spindles is inserted the object to be cut, which in the case represented is a tumbler 1. The lower end of the spindle 4 is provided with a suitably-shaped block or conical disk 2, of cork or wood faced with rubber, which disk is adapted to enter the tumbler and to bear against the inner side of the bottom for the purpose of centering the tumbler. Said spindle is forced against the glass article by means of a spring 8, bearing against a collar secured to the spindle, and the spindle is adapted to be raised in order to remove and exchange the glass article by means of the hand-lever 7, attached by links to a grooved collar 7'. The glass article rests upon the lower spindle 5, which at its top is provided with a disk 3, smaller in diameter than the bottom of the tumbler. The spindle 5 can be adjusted in height by means of a set-screw 6.

A revoluble shaft 9 is provided with a cylindrical sleeve 10, which is adapted to be moved longitudinally upon the shaft by means

of an angle-lever 50, and is provided with a cam 10'.

11 is a wheel which bears upon the sleeve 55 10 or cam 10', and is attached to a socket or slide 11', which is guided by a rod 12, and is forced upon the sleeve 10 or cam 10' by a spring 13. It is evident that the socket or slide 11' will not move so long as 60 the wheel 11 rolls upon the sleeve 10, while if the cam 10' be moved beneath the wheel 11 by means of the lever 50 the slide 11' will reciprocate in conformity with the shape of the cam or eccentric 10'. Such reciprocating motion is transferred to the grinding-wheels 24 and 24' by means of the sets of levers 14, 15, 17, 18, and 19 and 14', 15', 17', 18', and 19' in the following manner: The links 14 and 14' connect pivotally the socket or slide 11' 70 to the double-armed levers 15 and 15', which oscillate around the pivot 16, which is stationarily fixed to the bracket B of the frame A. The double-armed lever 15 is connected pivotally to the link 17, which in turn is connected pivotally to the swinging frame 18, in which the grinding-wheel 24 is journaled. The frame or lever 18 is shown in longitudinal section in Fig. 3, and consists of a bifurcated lever which is supported by and oscillates around an axle 30. This axle is located in a similarly-bifurcated lever 19, both lower ends of which are oscillatorily attached to a shaft 27, from which rotary motion is transferred to the grinding-wheel 24 in a manner hereinafter described. The shaft 27 is supported in stationary journals on the frame A. The upper end of the bifurcated lever 19 is connected to lugs of the frame A by means of a yielding spring 20, which tends to force 80 the lever 19 toward the spindle 4. From this construction it becomes evident that if an upward motion be imparted to the slide 11' the link 14 will be forced outward and the double-armed lever 15 will pull the link 17 85 downward, so as to raise the end of the bifurcated lever in which the grinding-wheel 24 is journaled, and simultaneously the grinding-wheel 24 is forced toward the spindle 4 by means of the bifurcated lever 19 and 90 spring 20.

Instead of using the link-connections 14, 15, and 17 to transfer the reciprocating motion of the slide 11 upon the swinging frame

18, the same may be accomplished by using a direct link-connection between the slide 11 and that part of the bifurcated lever 18 which is situated between the axle 30 and the grinding-wheel 24, as shown in Fig. 11. The combination of the bifurcated lever 19, oscillating around the shaft 27, with the bifurcated lever 18, oscillating around the axle 30, is a necessity if the grinding-wheel 24 is to be set 10 in revolving motion by a belt.

The shaft 27, which derives its revolving motion from a convenient source, is provided with two pulleys, pulley 28 communicating with pulley 28' of a corresponding second set 15 of levers, while pulley 29 drives the grinding-wheel 24, the belt passing from pulley 27 to pulley 31 upon the axle 30, and from there to the pulley 35 upon axle 34 and back by the idler-pulley 32, moving in swinging bearings 20 33, suspended from or oscillating around the axle 30 and again to the pulley 29. From the axle 34 of the grinding-wheel is suspended a trough 26, through which the periphery of the grinding-wheel moves. This trough collects and is partly filled with water or such substance as is applied to the cutting-surface of the wheel. In order that the grinding-wheel shall not cut too deeply into the glass, I employ a stop-guide 21, which allows the 25 grinding-wheel to approach toward the spindle 4 to a limited distance only. Such stop-guide is attached to lugs 22 and 23 on the brackets of the frame A, and may have any desired curvature or shape, so as to permit the 30 grinding-wheel to approach a little or large distance into grinding contact with the glass article, or to come into grinding contact with the article repeatedly, or at intervals during one reciprocating motion of the 35 40 socket-slide 11. The stop or profile guide 21 is situated so as to restrict the free motion of the grinding-wheel toward the glass article, and is preferably located, as shown in Figs. 1, 3, 6, and 8, in front of the axle 34, separated 45 from such axle by a sleeve 25, in which the axle revolves freely, and which is adapted to slide upon the profile-guide 21. The lower part of the guide is curved, so as to withdraw the grinding-wheel entirely from the object when 50 55 the wheel 11 is rolling upon the sleeve 10 or upon the lowest part of the cam 10', so as to allow the withdrawal and exchange of the glass article or so as to give it time to be turned partially to present a new face to be cut. The mechanism by which this latter operation is performed automatically consists of the following parts:

The spindle 4 is provided with a key-seat into which fits a key located in the miter 60 gear-wheel 43, so that if the miter gear-wheel be turned for a certain number of teeth the spindle 4 and thereby the glass object must follow. The gear-wheel 43 is operated by the miter gear-wheel 42. Upon the shaft 52 of 65 the miter gear-wheel 42 is a ratchet-wheel 41, Figs. 2, 4, and 7, into which meshes a pawl, Fig. 4, mounted upon an arm 49, radiating

from and oscillating around the axle of the ratchet-wheel. The arm 49 is connected by a pitman 40 to a wrist-pin 39 in the crank 38. 70 This wrist-pin is mounted upon a slide which is movable toward or away from the axle 53, so as to have a larger or smaller throw. The shafts 9 and 53 are connected by lock-gearing consisting of the wheels 37 and 36, (shown in Fig. 5,) constructed substantially as described in United States Patent No. 319,513, granted to me on the 9th day of June, 1885. By reason of this gearing-connection each of the shafts 9 and 53 performs a complete revolution; but 80 the shaft 37 completes its revolution in but a fraction of the time occupied by the shaft 9 in revolving once. The gear-wheel 36 is secured to the shaft 9 with reference to the cam 10', so that it causes the wheel 37 to revolve during that period of time in which the wheel 11 rolls over the cylindrical surface of the cam, which is of the same diameter as the sleeve 10, and thus the miter gear-wheels 42 and 43 are turned when the grinding-wheel 90 is in its lowest position and not in contact with the glass object. It is evident, if the ratchet-wheel 41 has, for instance, sixty teeth, that by adjusting the wrist-pin 39 so that the pawl catches three, four, five, or six teeth the 95 complete revolution of the miter gear-wheel 43 or of the glass article will have been performed in respectively twenty, fifteen, twelve, or ten revolutions of the shaft 9, and that the article will have been provided with twenty, 100 fifteen, twelve, or ten flutes. By substituting a ratchet wheel of seventy-two or of forty-eight teeth, tumblers with respectively twenty-four, eighteen, twelve, or twenty-four, sixteen, or twelve flutes can be produced simply by 105 varying the throw of the wrist-pin 39 accordingly.

In order to stop automatically the revolving of the object after the proper number of flutes have been produced, I have devised the following mechanism: Upon the miter gear-wheel 43 slides a double-armed lever 44, pivotally connected at 46 to a bracket of the frame A. The lever 44 is forced upon the gear-wheel 43 by a spring 45, and its lowest 110 part, which slides upon the wheel, is shaped like or is provided with a peg or pin. The gear wheel itself is provided with a hole, which in course of rotation moves beneath the pin of the lever, which thereupon is forced 115 down at one end and raised at the other end. The pawl 47, which is adapted to engage the ratchet-wheel 41, Fig. 4, is provided with a circular prolongation concentric with the axle 52, which prolongation moves through a link 120 suspended from the lever 44. If now the peg of the lever 44 drops into the hole of the miter-wheel, the pawl of the ratchet-wheel is raised from contact with the teeth of the ratchet-wheel, and although the shaft 9 may 125 continue to revolve the miter-wheel and the glass article will remain stationary. Simultaneously with this the knee-lever 50, operating the sleeve-cam 10', is actuated by the rod

51 and the lever 44, so that the cam 10' is withdrawn from beneath the wheel 11 and the grinding operation is stopped. After exchanging the tumbler the lever 44 is raised, and 5 this causes the cam 10' to move beneath the wheel 11, and the cutting will proceed automatically until the tumbler is fluted all around, when it will stop.

Instead of providing the web of the gear-wheel 43 with the hole or rest into which meshes the protruding pin or peg of the stop-lever 44, a separate revolving disk around the spindle 4 or around the axle 52 may be provided with such hole or rest, or such disk or 15 gear-wheel 43 may be provided with a peg or pin or lug, and the lever 44 be encountered by such peg or lug in the course of the revolution of the disk, and from such encounter of the peg and lever a motion can be derived 20 to raise the pawl and to actuate the slide-cam 10'.

In the apparatus shown in Fig. 1 the tumbler is being fluted simultaneously on opposite sides by two oppositely-situated grinding-wheels, and the tumbler needs to make but a half of a revolution, and consequently the miter gear-wheel 43 is provided with two stop-holes, as shown in Fig. 2. The application of 25 two oppositely-situated grinding-wheels not only accelerates the grinding operation by one-half, but it has the advantage of holding the object better centered by the opposed counter-pressures. To this end parts of the apparatus are duplicated, as shown in Fig. 1, 30 in which I have distinguished corresponding parts on opposite sides of the machine by reference-figures having the prime (') mark.

The apparatus illustrated in Figs. 6 and 7 is a modification of the apparatus above described, and the parts are indicated by reference-symbols distinguished by the exponent mark ^a. It differs from the first one in the relative motion between the object to be ground or cut and the grinding wheel or wheels, if 45 more than one be employed. In this modification the glass article 1^a, held and centered by the spindles 4^a and 5^a, is caused to perform a reciprocating motion for each revolution of the shaft 9^a by means of the cam 10^a and the 50 wheel 11^a rolling thereupon. The wheel 11^a transfers the reciprocating motion imparted to it from the cam upon the casting B^a, which carries the brackets in which the spindles 4^a and 5^a are journaled. This casting B^a slides 55 in guides C^a, attached to the frame or bed-plate A^a, and receives its downward motion from the cam 10^a, while its upward motion is effected by the springs 53^a. The cam-sleeve 10^a is operated by the angle-lever 50^a, as described above. The axle 34^a of the grinding-wheel 24^a is journaled in the bifurcated sliding bearing 18^a, Figs. 6, 8, and 10, which is forced toward the glass object by the spring 20^a. The bifurcated bearing 18^a moves in a 60 stationary guide 55^a, which is firmly connected with the frame A^a. The stop-guide 21^a, which controls the motion of the grinding-wheel to-

ward the glass object, and which causes the grinding-wheel to recede entirely from contact with the glass article, is attached to the 70 casting B^a and participates simultaneously with the glass object in the reciprocating motion of this casting. The revolving motion is imparted to the grinding-wheel 24^a, not by a belt, as described with reference to Figs. 1 75 and 3, but by means of a flexible shafting 54^a, the end of which is attached directly to the axle 34^a by means of a union, as indicated in Fig. 8. The flexible shafting facilitates considerably the construction for a multiple 80 grinding apparatus, since it dispenses entirely with the clumsy or bulky construction of the flexible knee-lever combination, which is unavoidable if a belt is used. Two, three, or more grinding-wheels can thus easily be 85 located at proper distances around the glass object, decreasing correspondingly the time necessary for the grinding operation, besides the glass object is not exposed in such case to a one-sided pressure, which causes considerable 90 breakage, but the various grinding-wheels can be located so as to counteract each other in the pressure exerted upon the glass object. The automatic revolution of the glass article and the automatic stopping after the 95 cutting has been performed all around it may be performed by the same mechanism as described above.

In Figs. 9 and 10 an arrangement is shown by means of which the grinding-wheel revolving in movable or traveling bearings can be supplied with water or with emery and oil. The receptacle 56 is located upon a support which is loosely attached to the axle 34, and which is counterbalanced by the 105 weight 57.

In place of the grinding-wheels 24, polishing-wheels may be substituted, or while the grinding of the object is performed upon one machine the polishing may be performed upon a 110 second machine of the same construction. I therefore wish to include in the term "grinding-wheel," used in the claims, also a polishing-wheel.

A peculiarity of my apparatus is that it enables me to produce glass objects with concave and with convex flutes of a short radius extending parallel to the axial line of the object, which is not feasible with the present well-known flute-cutting machine, because the 115 120 grindstones of the latter are revoluble in a plane forming an angle with the axial line of the revoluble glass object, while in my machinery the grinding-wheel is revoluble in a plane parallel to the axis of the spindle supporting the glass object.

The advantages of my invention will be appreciated by those skilled in the art. The machine is strong and durable in its construction, is easy to operate, and facilitates greatly 130 the work of grinding and polishing. The parts of the apparatus may be modified in many ways in form, construction, and the relative position of the parts without departing

from the scope of my invention, as stated in the following claims.

I claim—

1. In apparatus for grinding or polishing 5 glassware, a revoluble spindle for centering and holding the glass object adapted to be revolved intermittently and a grinding-wheel journaled in movable bearings and adapted to be forced toward the spindle.
- 10 2. In apparatus for grinding or polishing glassware, a spindle revoluble in stationary bearings for centering and holding the glass object, a grinding-wheel journaled in movable bearings and adapted to be moved toward the 15 spindle, and a profile-guide shaped and placed so as to regulate the motion of the grinding-wheel toward the glass object.
- 15 3. In apparatus for grinding or polishing glassware, a revoluble spindle for centering 20 and holding the glass object, and a plurality of grinding-wheels journaled in movable bearings adapted to be moved simultaneously toward the spindle.
- 25 4. In apparatus for grinding or polishing glassware, a revoluble spindle for centering and holding the glass object, a grinding-wheel journaled in movable bearings and adapted to be moved toward the spindle, a revoluble shaft provided with a sliding cam- 30 sleeve, a lever adapted to actuate the cam-sleeve, gearing on the shaft adapted to actuate a crank and adapted to rotate intermittently the revoluble spindle centering the glass object, and a pitman, pawl, ratchet-wheel, 35 and intermediate gearing.
- 35 5. In apparatus for grinding or polishing glassware, a revoluble spindle for centering and holding the glass object, a grinding-wheel journaled in movable bearings and 40 adapted to be moved toward the spindle, a revoluble shaft provided with a sliding cam-sleeve, a lever adapted to actuate the cam-sleeve, and gearing upon the shaft adapted to actuate a crank and adapted to rotate inter- 45 mittently the revoluble spindle centering the glass object.
- 45 6. In apparatus for grinding or polishing glass objects, an automatic revolving and stopping arrangement for revolving intermit- 50 tently and setting at rest the glass object, consisting in a spindle centering and holding the glass object, a wheel concentric with such spindle, in combination with a continuously-revoluble shaft and intermediate connections 55 between the shafts and the spindle gearing a crank-shaft with a pitman, a pawl actuated by the pitman, a ratchet-wheel and gear-wheels adapted to transfer the motion from the ratchet-wheel axle upon the spindle, a 60 revoluble disk or wheel provided with one or
- more rests, and a lever adapted to meet such rest in course of rotation of the disk, and connections, substantially asdescribed, adapt- 65 ed to transfer the motion imparted to the lever upon the pawl of the ratchet-wheel, where- by the further rotation of the spindle is pre- vented.
7. In a device for intermittently rotating a glass object held between the spindles of a grinding apparatus, a lock - gearing at- 70 tached to a steadily revoluble shaft and pro- vided only on a part of the circumference with a series of cogs, and a second gear-wheel attached to a crank-shaft, which gear-wheel is provided with a locking-tooth and a series 75 of cogs corresponding in number to the cogs of the first gear-wheel, which lock-gearing is so constructed and related to the first gear- wheel that while the first performs a single steady rotation one single and full rotation 80 is performed intermittently by the second gear-wheel.
8. In apparatus for grinding or polishing glassware, a revoluble spindle for centering and holding the glass object and a plurality 85 of grinding - wheels journaled in movable bearings, flexible shafting connected to the axle of each grinding-wheel, which bearings of the grinding - wheels are adapted to be forced from various directions simultaneously 90 toward the spindle, and profile-guides ar- ranged around the revoluble spindle in the pathway of the axles or of the bearings of the grinding-wheels.
9. An apparatus for grinding or polishing 95 glassware, consisting of a revoluble spindle for centering and holding the glass object journaled in bearings attached to a vertically- movable slide adapted to receive reciprocating motion from a revoluble shaft by means 100 of a cam, and a profile-guide attached to the reciprocating slide, in combination with a grinding-wheel revoluble in a sliding bearing adapted to be moved toward the spindle of 105 the grinding machinery by spring power and controlled in its motion toward or away from said spindle by the profile-guide.
10. In apparatus for grinding or polishing 110 glassware, a spindle for centering and hold- ing the glass object, a grinding-wheel adapted to revolve in a plane parallel to the axle of the spindle, and a profile or stop guide adapt- ed to control the approach of the grinding- wheel toward the spindle.
- In testimony whereof I have hereunto set 115 my hand this 23d day of April, A. D. 1890.
